HYDROCARBON CONVERSION

Thomas S. Mertes, Wilmington, Del., assignor to Sun Oil Company, Philadelphia, Pa., a corporation of New Jersey

Application February 13, 1956, Serial No. 565,100

2 Claims. (Cl. 208—96)

This invention relates to the catalytic conversion of hydrocarbon fractions and more particularly to a process for catalytically cracking residual oils wherein an increased yield of gasoline and valuable aromatic fractions may be obtained.

While residual crude oils are not favored as the charge to a catalytic cracking operation since they contain large amounts of coke-formers and catalyst-deactivating metal compounds, in areas where heavy fuel is in over-supply, it has been found necessary, from an economic standpoint, to crack such stocks; and commercial processes, such as the Houdresid process, have been developed to process reduced crudes. In such processes, the crude, together with recycle hydrocarbons, is charged along with a considerable quantity of steam, which serves to reduce the partial pressure of the hydrocarbons and lessen coke deposition, to a reactor in which the hydrocarbons are contacted at temperatures of from about 850° F. to 1000° F., with a cracking catalyst such as bauxite, activated clay or synthetic silica-alumina gel. The products from the cracking operation are then fractionated to produce a C₄ and lighter cut, a gasoline cut, and higher boiling hydrocarbons. This higher cut contains the more refractory components of the charge and cannot be recycled in its entirety to the cracking operation since excessive amounts of coke would be laid down on the catalyst leading to rapid deactivation thereof. In order to make the cracking process economically attractive, however, some of this higher boiling must be recycled, otherwise some 60 percent of the cracked products must be sold as low-priced fuel oils.

One presently operating commercial process solves the problem by fractionating the hydrocarbons boiling higher than gasoline into a fraction boiling in the 400-600° F. range, which is sold as No. 2 fuel oil, a gas oil fraction boiling largely between 600° F. and 800° F., which is recycled to the cracking step, and a highly refractory bottoms, boiling largely above 800° F. which is useful only for sale as low-priced heavy fuel oil. By such fractionation, about 10% of the cracked products are converted to No. 2 fuel, about 40% to recycle gas oil, and about 7% to heavy fuel. The No. 2 fuel is highly unstable, due to the presence of diolefins and other gum formers, and must be further up-graded at considerable expense, as by hydrogenation, in order to render it commercially salable. The recycle gas oil, while usable in the process, still contains a large amount of carbon-formers, which deposit an excessive amount of coke during the cracking operation, necessitating the provision of overly large catalyst regeneration facilities in order to burn the carbon off the catalyst.

Proposals have also been made for treating cracked products boiling above gasoline by solvent extraction to remove aromatics and thus reduce the coke-formers in the recycle to the cracking step. Thus, one prior art proposal has been to fractionate catalytically cracked products to recover gasoline and lighter fractions, a gas oil fraction, and a tar bottoms. All, or the heavier por-

2

tion, of the gas oil is solvent extracted to yield a raffinate which is recycled to the catalytic cracking step, and an extract which is thermally cracked. Another prior art proposal is to solvent extract all of the cracked products boiling above gasoline resulting from the catalytic cracking of a gas oil, to recycle the raffinate to the catalytic cracking step, and to send the extract to thermal cracking.

The present invention is also concerned with a process in which a portion of the cracked products resulting from the catalytic cracking of a hydrocarbon feed stock is solvent extracted, with the raffinate being returned to the cracking step, but is limited to a process in which the hydrocarbon feed is a reduced crude. In accordance with the invention, the cracked products are fractionated to yield a gasoline fraction, a fraction boiling in the 400-500° F. range, a gas oil fraction, and a bottoms fraction comprising from about 25% to 35% by volume of the feed to the cracker, and boiling largely above 750° F. The 400-500° F. fraction is a light-colored, stable product valuable as a No. 2 fuel oil component. The gas oil fraction is recycled to the cracker without further treatment and will usually comprise about 15 to 25 percent of the feed thereto. The bottoms fraction is solvent extracted to remove about 25 to 35 percent thereof as extract, and the raffinate is returned to the cracker as a feed component. The extract may then be fractionally distilled to yield, as an overhead product, an aromatic solvent which, at present market prices, is worth more than gasoline and a bottoms product valuable as carbon black oil.

The process of the present invention distinguishes from the prior art in many respects. First, no products of low value are produced, such as the heavy fuel oil produced in the commercial process described above, or the tars produced in the prior art process described above. Second, a stable No. 2 fuel oil is produced. This fraction is largely lost in processes in which the light gas oil is recycled to catalytic cracking, since it is of relatively low molecular weight, and since cracking catalysts direct splitting of the molecule toward the center, products of cracking this fraction are largely coke and normally gaseous hydrocarbons. A third point of differentiation is that only a small portion of the cracked products, including all the highest boiling components, is extracted. By proceeding according to the present invention, it is possible to minimize the size of the extraction equipment, and also to produce a valuable aromatic solvent and a carbon black oil from the highest boiling components of the cracked products. Neither of these products are produced in the prior art processes.

In order that those skilled in the art may more fully appreciate the nature of my invention and the method of carrying it out, an example will be more fully described in connection with the accompanying drawing which is 55 a diagrammatic flow sheet of the process.

Fresh feed, which is a reduced Mid-Continent crude of 27° A.P.I. gravity, having an initial boiling point of 490° F., a 50% point of 660° F., with 87% over at 1024° F., is introduced to the process in the amount of 60 7100 barrels per day (hereinafter referred to as b./d.) and is mixed with 2740 b./d. of a recycle raffinate stream and with 2460 b./d. of a distillate recycle stream obtained from a later stage of the process as hereinafter described. The mixed feed, in the amount of 12,300 b./d., is then 65 passed through furnace 2 in which it is heated to about 925° F., and thence through line 3 to a reactor 4, in which it is contacted with a silica-alumina catalyst and steam in a manner well known to the art at a temperature of about 925° F.

Conversion products are taken through line 5 to fractionating tower 6, from which 1840 b./d. of C₄ and lighter hydrocarbons are taken overhead for further proc-

essing through line 7. A side stream of 4220 b./d. of gasoline boiling from 110-430° F. is recovered through line 8; 650 b./d. of a side stream boiling from 390° F. to 525° F. are taken off through line 9 for sale as No. 2 fuel oil; and 2460 b./d. of recycle gas oil are removed from a lower point in the column and are passed through line 10 to admixture with the incoming fresh feed.

Bottoms amounting to 3790 b./d. is removed from fractionator 6 through line 11 and is passed to a furfural extraction plant 12 in which it is separated into 2740 b./d. of a 20° A.P.I. raffinate, which is cycled through line 13 to admixture with incoming fresh feed, and 1050 b./d. of aromatic extract of 1° A.P.I. gravity. Furfural extraction plant 12 consists of a contacting tower or other contacting means, together with solvent recovery facilities. Since such facilities are well known to the art, no purpose would be served by describing them in detail herein.

The extract, which is over 90% aromatic, is taken through line 14 to a fractionating tower 15, in which it is separated into 760 b./d. of an aromatic solvent and 290 b./d. of a high-grade carbon black oil.

The improvement in results obtainable by my new process over those obtained in conventional cracking of residual stocks without solvent extraction may be seen from the following table, in which column A shows the product distribution, in percentages of the total feed to the catalytic cracker, obtained by proceeding according to present-day commercial practice, that is, by recycling 5200 b./d. of distillate gas oil to the process to make up a total of 12,300 b./d. of feed to the cracker. Column B shows the results obtained when operating according to the procedure of the foregoing example. In column A, coke formation and dry gas formation were the limiting factors, whereas, in column B, conditions were adjusted to give about 35% gasoline yield per pass.

Table I

Product—Percent of Feed	A	B	40
Dry Gas (C ₃ and lower).....	6.8	5.9	
Butylenes.....	4.8	4.8	
Penitanes and Butanes.....	4.7	4.2	
C ₆ +Gasoline.....	28.2	34.3	
No. 2 Fuel.....	10.6	5.3	
Recycle Gas Oil.....	42.3	20.0	45
Raffinate Recycle.....	0.0	22.3	
Residual Heavy Fuel.....	6.6	0.0	
Aromatic Solvent.....	0.0	6.2	
Carbon Black Oil.....	0.0	2.3	
Total Recovery, C ₄ and higher.....	97.2	99.4	
Coke make, lb./hr.....	6,000	4,900	

As may be observed from the foregoing, by proceeding according to the present invention, gasoline production may be increased by 21.5%, and two new and valuable products, aromatic solvent and carbon black oil are produced in good yield. In addition, losses to coke and dry gas have been considerably reduced, low-priced heavy fuel oil has been eliminated as a product, and total recovery of C₄ and higher hydrocarbons has been increased by 2.2%. Reduction in coke yield is particularly important in those installations in which catalyst regeneration capacity is the limiting factor, since with lower coke make, a larger amount of feed hydrocarbons may be processed in the same equipment.

I claim:

1. A process for the conversion of residual petroleum fractions which comprises mixing a reduced crude feed stock with a recycle gas oil fraction and a recycle raffinate fraction, both of said latter fractions being recovered from a later stage of the process; contacting the mixture with a cracking catalyst in a cracking zone at cracking temperatures; recovering an effluent from the cracking zone; subjecting the effluent to fractional distillation to recover as separate streams a C₄ and lower fraction, a gasoline fraction, a No. 2 fuel oil fraction boiling in the 400-500° F. range, a recycle gas oil fraction, and a bottoms fraction amounting to about 25 to 35 volume percent of the total feed to the cracking zone and boiling largely above 750° F.; recycling the recycle gas oil fraction to admixture with the reduced crude feed stock; contacting the bottoms fraction with a solvent selective for the extraction of aromatic hydrocarbons; recovering a solvent-free raffinate of reduced aromaticity as compared to the bottoms fraction, in an amount equal to from about 65 to 75 volume percent of the bottoms; recycling the raffinate to admixture with the reduced crude feed stock; recovering a solvent-free extract from the solvent extraction step, subjecting the extract to fractional distillation, recovering as an overhead fraction an aromatic solvent oil, and recovering a carbon black oil as a bottoms fraction.

2. A process for the conversion of residual petroleum fractions which comprises charging a feed stock comprising a reduced crude fraction, a recycle gas oil fraction, and a recycle raffinate fraction, the latter two fractions being recovered from a later stage of the process to a cracking zone, contacting the feed therein with a cracking catalyst at cracking temperatures, recovering an effluent from the cracking zone, subjecting the effluent to fractional distillation to recover hydrocarbons boiling below about 500° F., a gas oil fraction boiling above 500° F., and a bottoms fraction in volume equalling about 25 to 35 volume percent of the feed to the cracking zone and boiling largely above 750° F., recycling the gas oil fraction to the cracking zone, contacting the bottoms fraction with a solvent selective for the extraction of aromatic hydrocarbons, recovering a solvent-free raffinate of reduced aromaticity as compared to the bottoms fraction in an amount equal to from about 65% to 75% of the bottoms, recycling the raffinate to the cracking zone, recovering a solvent-free extract from the solvent extraction step, subjecting the extract to fractional distillation, recovering as an overhead fraction an aromatic solvent oil, and recovering a carbon black oil as a bottoms fraction.
